UNITED STATES PATENT OFFICE.

GEORGE N. LEMMON, OF BIRMINGHAM, ALABAMA.

EXTRACTOR FOR COTTER PINS, NAILS, AND THE LIKE.

Application filed January 29, 1926. Serial No. 84,651.

My invention relates to an extractor for cotter-pins, tacks, nails and the like, and particularly to extractors of the plier type adapted to be gripped in the hand. Among 5 the principal objects of my invention are, (1) to provide an extractor which will withdraw a pin or nail which has but a small portion accessible; (2) to provide an efficient manually operated extractor which is simple 10 and inexpensive to manufacture.

While the gripping jaws of my extractor may be shaped in any fashion appropriate to the service for which it is designed, I have 15 illustrated jaws primarily intended for clamping upon a cotter-pin, and in the accompanying drawings,

Fig. 1 is a side elevation of an extractor in which my invention is embodied in this form;

20 Fig. 2 is a side elevation corresponding to Fig. 1, but illustrating the operation of the extractor;

Fig. 3 is a side elevation of jaw lever;

25 Fig. 4 is a side elevation of the fulcrum lever;

Fig. 5 is a broken plan of the fulcrum end of the latter;

Fig. 6 is a side elevation of the link jaw member; and

30 Fig. 7 is an end elevation of the extractor as viewed from the left in Fig. 1, showing how the parts are connected together.

Cotter-pin extractors are commonly provided with a point intended to enter and engage the eye of the cotter-pin. When 35 cotter-pins are in good order they are readily removed by a pair of ordinary pliers. In actual practice, however, cotter-pins are often encountered which have been ham-
mered in, the eye having been thereby closed or even broken. Often, also, so small a portion 40 of the pin is accessible that it is extremely difficult to get a grip on the exposed end with an ordinary pair of pliers. The 45 present device may be successfully used even under these conditions.

My device includes a pair of clamping jaws such as have long been in general use in nail extractors. Cotter-pins, however, 50 are generally used in places where a nail extractor cannot be used, as there is seldom a surface upon which the fulcrum arm of the nail extractor can be rested. The addition of the extra handle member makes the new device easily operated and effective in

the difficult cases for which no other device is at all suitable.

Referring to the drawings, the appliance shown comprises a manually gripped lever arm 10 shaped at one end to form a jaw 11, 60 and an opposed manually gripped lever arm 12 shaped at its corresponding end to form a fulcrum fork 13 which straddles the jaw 11. While a fork end is preferable it is not necessary. It is essential only that the ful- 65 crum lever 12 shall have an end which rests upon the support, e. g. a nut from which the cotter pin is extracted.

Interposed between and connecting the two lever arms 10 and 12 is a link 15 piv- 70 oted at 16 and 17 to the arms 10 and 12. One free end of the link 15 is shaped to form a jaw 18 opposed to the jaw 11, and also straddled by the forked end 13 of the arm 12. At its opposite free end the link is pro- 75 vided with a tail 19 engaged by the free end of a leaf spring 20 secured at 21 to the arm 12. The effort of the spring tends to move the jaws 18 and 11 through the fork 13 of the lever arm 12.

80 The operation of the extractor is readily followed from Figs. 1 and 2. To open the jaws the hand grip ends of the arms 10 and 12 are separated. The fork 13 is held by the spring 20 above the gripping ends of the 85 jaws 11 and 18. The latter may now be positioned on opposite sides of the head of the cotter-pin 23. When the arm 10 is pressed toward the arm 12 by the grip of the hand, the jaw 11 approaches the jaw 18, and 90 clamps the cotter-pin head. As the arms 10 and 12 are further closed, the forked fulcrum end of the arm 12 swings on the pivot 17 toward the plane of the jaw ends since the jaw arm 10 is now halted by its engagement 95 with the cotter-pin. The fork then bears upon the support 24, which may be the face of the nut 22 through which the pin 23 passes, and a further gripping effort upon the arms 10 and 12 is exerted through the 100 link 15 to lift the jaws 18 and 11 straight away from the nut 22. The pin 23, thus started through its hole in the nut, may now be pulled straight through the hole by the bodily displacement of the extractor 105 away from the nut. If its frictional engagement is still too great to permit this, however, a second grip may be taken further down on the cotter-pin, and the opera- 110 tion repeated.

The physical structure of the parts is rugged, simple and serviceable. It may be varied in detail while still embodying the thoughts which underlie what I claim as my invention.

I claim:

1. An extractor for cotter-pins and the like, comprising a pair of levers, a link connecting the same and having a jaw end, one 10 of said levers having a jaw end cooperating with the link jaw, the other lever having a fulcrum end which moves across the plane in which the jaws meet, when the operating levers approach each other.
- 15 2. An extractor of the type described, comprising a lever with forked fulcrum end adapted to straddle the head of a pin or the like, and a pair of cooperating jaw members pivotally connected together, one of the jaw 20 members being pin connected to the fulcrum lever, said jaw members playing across the plane of said forked end of the fulcrum lever.
- 25 3. An extractor comprising a jaw lever, a fulcrum lever, a link jaw cooperating with the lever jaw, a pivotal connection in the neighborhood of the jaw between the link and jaw lever, and a pivotal connection between the link and fulcrum lever at a point 30 remote from the link jaw.
- 35 4. An extractor comprising a jaw lever, a fulcrum lever, a link jaw cooperating with the lever jaw, a pivotal connection in the neighborhood of the jaw between the link and jaw lever, and a pivotal connection between the link end fulcrum lever at a point 40 remote from the link jaw, together with spring means engaging the link tending to urge the clamping jaws past the fulcrum lever.
- 45 5. In an extractor for cotter-pins or the like, a pair of jaws pivotally connected together and an extension on one of said jaws in combination with a handle member to which said extension is pivotally connected, there being a fulcrum end rigid with said handle member.
- 50 6. In an extractor for cotter-pins or the like, a pair of jaws pivotally connected together, a rigid handle extension on one jaw, and a rigid extension on the other jaw, in combination with a second handle member pivotally connected with said second extension there being a fulcrum end rigid with 55 said second handle member.
7. In an extractor for cotter-pins or the like, a pair of jaws pivotally connected together, and an extension on one of said jaws,

in combination with a handle member to which said extension is pivotally connected, 60 there being a fulcrum end rigid with said handle member said handle member being operable independently of the operation of the jaws.

8. In an extractor for cotter-pins or the like, a pair of jaws pivotally connected together, a rigid handle extension on one jaw, and a rigid extension on the other jaw, in combination with a second handle member pivotally connected with said second extension, said second handle member having a fulcrum arm which extends from the pivot 70 towards the jaws.

9. In an extractor for cotter-pins or the like, a pair of jaws pivotally connected together, a rigid handle extension on one jaw, and a rigid extension on the other jaw, in combination with a second handle member pivotally connected with said second extension, said second handle member having an 80 arm which straddles the jaws and extends to their gripping point.

10. In an extractor for cotter-pins or the like, a pair of jaws pivotally connected together, a rigid handle extension on one jaw, 85 and a rigid extension on the other jaw, in combination with a second handle member pivotally connected with said second extension, said second handle member having a fulcrum end which extends to the gripping point of the jaws.

11. In an extractor for cotter-pins or the like, a pair of cooperating clamping jaws, and a handle rigidly attached to one of said jaws, in combination with a second handle 95 pivotally attached to the second jaw, and an arm rigid with said second handle extending from the point of attachment toward the clamping contacts of the jaws said arm being adapted to act as a fulcrum for 100 the jaws.

12. In an extractor for cotter-pins or the like, a pair of cooperating clamping jaws, and a handle rigidly attached to one of said jaws, in combination with a second handle 105 pivotally attached to the second jaw, an arm rigid with said second handle extending from the point of attachment toward the clamping contacts of the jaws said arm being adapted to act as a fulcrum for the 110 jaws, and spring means tending to keep the second jaw in fixed relation with its handle.

In testimony whereof I have signed my name to this specification.

G. N. LEMMON.
